(57) **CLAIM**

The ornamental design for a bottle accessory, as shown and described.

DESCRIPTION

FIG. 1 is a perspective view of the bottle accessory showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof; the bottom view being identical to the top view.

The broken lines in the drawings illustrate the portions of the design that form no part of the claim.
